UNITED STATES PATENT OFFICE

2,516,783

METHOD OF AND MECHANISM FOR
APPLYING STAMPSAlbert J. Matter, Park Ridge, Ill., assignor to
American Decalcomania Company, Inc., Chi-
cago, Ill., a corporation of Illinois

Application July 27, 1948, Serial No. 40,888

10 Claims. (Cl. 216—1)

1 My invention relates to a method of applying stamps and a mechanism for use therewith.

Cigarettes are transported and sold in cardboard cartons, each of which contains ten packages of twenty cigarettes each. Tax stamps, such as those associated with State sales taxes on cigarettes, must be applied to each individual package to satisfy the applicable laws. Since such stamps are frequently imposed by State or local governments and consequently are applied to a relatively small proportion of the total number of cigarette packages sold, it is not feasible to apply them at the factory and it is desirable to provide an efficient method of applying them to cigarettes packed in cartons.

It is accordingly a general object of the present invention to provide an improved method of and means for applying stamps to packages contained in a jacket or carton.

Another object of the present invention is to provide an improved method of and means for applying stamps to packages contained in a jacket or carton and which is capable of receiving unopened cartons and delivering them in a sealed condition after being stamped.

Further, it is an object of the present invention to provide an improved method of and means for applying stamps to packages contained in a jacket or carton and which embodies features of combination and arrangement rendering it simple and effective and suitable for high speed operations.

Yet another object of the present invention is to provide an improved means for stamping a plurality of packages contained in a carton and which is adapted to receive a single sealed carton and execute the required operations without wastage of stamps or gluing fluid.

The novel features which I believe to be characteristic of my invention are set forth in the appended claims. My invention itself, however, both as to its organization and method of operation, may best be understood by reference to the following description taken in connection with the accompanying drawings in which:

Figure 1 is a top plan view of a complete machine incorporating the features of the present invention;

Figure 2 is an isometric view of a package of the type capable of being received by the machine of Figure 1;

Figures 3 to 9 are cross-sectional views of the package taken through axis 3—3, Figure 2, and showing the successive conditions assumed thereby during the stamp-applying operations;

2

Figure 10 is a side elevational view of the mechanism of Figure 1;

Figure 11 is a greatly enlarged fragmentary top plan view like Figure 1 but with parts removed to show more clearly the underlying elements;

Figure 12 is a greatly enlarged fragmentary cross-sectional view through the axis 12—12, Figure 1;

Figure 13 is a greatly enlarged fragmentary cross-sectional view through the axis 13—13, Figure 1;

Figure 14 is a greatly enlarged fragmentary cross-sectional view through the axis 14—14, Figure 1;

Figure 15 is a cross-sectional view through the axis 15—15, Figure 1;

Figure 16 is an enlarged fragmentary portion of Figure 10 with parts broken away to show more clearly the construction of otherwise hidden elements;

Figure 17 is an enlarged fragmentary top plan view showing the mechanism provided to apply glue to the flap of the carton; and

Figures 18 to 21 are fragmentary cross-sectional views through the axes 18—18, 19—19, 20—20 and 21—21, Figure 1, respectively.

The general structure of a machine embodying the present invention and capable of performing the process thereof is shown in Figure 1. This machine incorporates a track-defining structure T, upon which the cartons of cigarettes are placed. This structure incorporates elements operative to impart step-by-step movements to the cartons to propel them from the right hand end, Figure 1, upon which they are received, to the left hand end, where they may be removed.

A tank F is mounted above the track T and includes elements operative to paint gluing fluid on successive pairs of cigarette packages as they travel by. A stamper mechanism, S, is located adjacent the tank F and operates to press a pair of stamps against the painted surfaces of the successive pairs of packages immediately after the painting operation. This mechanism incorporates stamp feeding and cutting elements in addition to the stamp pressing mechanism.

Motion is imparted to the movable elements of track T, tank F, and the stamping mechanism S by the motor M which is connected to these elements by means described in further detail hereafter.

The stamping process

Before describing the detailed constructional features of the machine of Figure 1, the successive

steps in the process performed thereby, will be described with reference to Figure 1 to 10.

As shown in Figure 2, the carton of the type to which the present invention is applicable is made of cardboard having top, end, and side walls enclosing a total of 10 packages, 20a, 20b, 20c, etc., positioned in an array of successive pairs. As shown best in the cross-sectional view of Figure 3, the top of the carton is closed by the tongue 22 which is received beneath the top wall member 24. The latter is held in position by suitable adhesive applied to the end lips 24a and 24b which anchors the same to the end walls of the carton. A spot of glue is also applied between tongue 22 and top wall member 24 near the longitudinal center of the carton.

The carton C is manually inserted in the right hand end of the track T, Figure 1. In this operation, the triangular knife 26 rides into the space between the tongue 22 and wall 24. The carton is then manually shifted to the right hand end of the machine to cause the edge 26a of knife 26 to sever the connection between wall 24 and the lip 24a, Figure 2. The carton is then manually shifted in the left hand direction to cause the edge 26b of knife 26 to sever the connection between wall 24 and the lip 24b, and separates tongue 22 from top wall member 24 at the glue spot.

When the wall 24 is severed from lips 24a and 24b, this wall and the tongue 22 spring to a partially open position. Moreover, the moving elements of track T take hold when the lip 24b has been severed and cause the carton to progress in step-by-step movements in the left hand direction, Figure 1.

As the carton progresses in its travel, the prong 27 rides underneath the tongue 22 and the wall 24. This prong is shaped to define cam elements which guide the tongue 22 and wall 24 to the upright positions of Figure 4 and subsequently to the open positions of Figure 5.

Just prior to the time it reaches the operating position of tank F, the carton actuates a trigger which causes successive operating movements of the glue fluid painting mechanism in timed relation to the step-by-step movements of the carton. This causes each pair of packages successively to receive the spots of glue fluid or solvent 28, Figure 6.

After travelling past the tank F, the tongue 22 of the carton C travels over the gluing roller 140a, Figure 10, which paints the lower face thereof with glue as indicated at 30, Figure 7.

Actuation of the trigger also causes the stamping mechanism S, Figure 1, to operate in timed relation to the step-by-step movements of the carton, thereby applying the stamps 32 to the spots of glue fluid as indicated in Figure 8.

Finally continued step-by-step movement of the carton C under the action of the track T carries the carton to the guides or cams 34 and 36. The former folds the tongue 22 down against the packages in the carton and the latter folds the wall 24 down on that tongue. The glue 30 then cements these members together to define a closed carton of cigarette packages which may then be removed from the machine.

The track

The track T is defined by a pair of vertical guide walls 38 and 40, Figures 1 and 12, which snugly receive the carton C, as indicated in Figure 12. The bottom of the track is defined by the carriage 42, Figures 1 and 10. This carriage

comprises an elongated groove bar 42a, Figure 13, having a succession of spaced carton-engaging pawls 42b, Figures 1 and 10.

The track T is supported by the cast frame 52 which receives the adjustable mounting bolts 142 which sustain the track. These bolts are received in suitable openings in the side support member 55, Figure 10, which member also defines a pair of spaced tracks 55a and 55b which receive the rollers 43 which in turn support the movable bar 42a.

The construction of pawls 42b may best be seen in the enlarged fragmentary cross-sectional view of Figure 15. As shown, each pawl is held against the web portion of bar 42a by the screw 42c. The spring 42d is received between the pawl and the web portion of bar 42a and serves to bias the pawl to the upper or engaging position. Movement of the pawl under this bias is limited by engagement with the head of screw 42c and engagement of the heel portion 42e of the pawl with the web portion of bar 42a.

Reciprocating movements are imparted to the bar 42a by the crank assembly 44, Figure 10. This assembly includes a crank arm 44a pivotally attached to the depending bracket 44b which is in turn attached to the bar 42a. At its other end, the crank arm 44a is pivotally attached to the wheel 44c.

The motor M imparts rotation to wheel 44c by the mechanical connections which may be traced from motor M, through belt 46 to the pulley 49 which in turn rotates inner shaft 50 and wheel 44c. This structure is best seen in the views of Figures 1 and 14.

As the wheel 44c rotates under the driving torque imparted by motor M, the bar 42a of track T executes reciprocating movements. If a carton is on the track T, the pawls 42b immediately thereunder are depressed by the weight thereof. However, the successive reciprocations of bar 42a cause the last pawl under the carton to snap upwardly on the extreme movement in the right hand direction of Figure 1. Upon subsequent movement to the left, this pawl engages the rear of the carton and pushes it forwardly in accord with the magnitude of the reciprocating movements. Hence each reciprocating movement of the bar or carriage 42a imparts a predetermined movement to the carton, thus causing step-by-step carton movements.

The crank assembly 44 is dimensioned to cause reciprocations of bar 42a in accord with the center-to-center spacing of the successive packages 20a, 20c, 20e, etc., in the carton C, Figure 2. Consequently, each step-by-step movement of the carton advances each package to the position previously assumed by the adjacent package.

The tank mechanism

It is the function of the tank F to paint each pair of packages with solvent or gluing fluid preparatory to the application of the stamps. The structure of this mechanism is best seen in the views of Figures 1, 10, and 12. As shown, this tank includes a housing 46 defining a chamber in which the solvent or gluing fluid is placed. This housing is supported from the upstanding fixed post 48 by the brackets 46a and 46b which have openings to receive that post. The compression spring 50 bottoms against bracket 46b and the base 52 to bias tank F to the position shown in Figure 12.

Successive downward shifting movements are imparted to the tank F by the rocker arm 54,

This arm is pivotally supported by shaft 56 and at end 54a rides on the lower bracket 46b as shown in the broken-away portion of Figure 12. The adjusting screw 57 and locking nut 57a provide control of the up and down movements of the tank F.

The end 54b of rocker arm 54 is bifurcated and receives roller 54c which forms a cam follower for cam 58. The operation of this cam is described in further detail hereafter.

Successive downward movements of the tank F in response to movements of rocker arm 54 cause the felt pads 60 to strike the tops of the cigarette packages 20a and 20b, Figure 12, thereby painting them with the gluing fluid or solvent.

Simultaneously, with the foregoing movement, additional gluing fluid is released into the solvent applicators 62. As indicated in the broken away section of Figure 12, and in the cross-sectional view of Figure 16, these applicators comprise brass bodies to which the pads 60 are attached by plates 61 and which are bored to provide channels from tank 46 to the pads. Leakage of fluid from tank 46 to the applicators is prevented by the balls 64 which are biased upwardly by springs 64a and which mate with suitable annular seats formed in the upper portions of the channels.

The balls 64 are successively pushed away from the annular seats by action of the push rods 66. These shift downwardly relative to tank 46 in accord with the movements of the rocker arm 54, thereby entrapping fluid in the channels 64b and moving balls 64 by the resultant fluid pressure against them. These shifting movements of the push rods 66 are produced by rocker arm 68 which is pivotally attached to the bracket 46c on tank 46 and which rests at end 68a against the top of the post 48. The opposite end 68b of the rocker arm 68 bottoms against the bridge 70 connecting the two push rods 66.

The bridge 70 has openings snugly receiving rods 66 and is held thereon by the opposed nuts 71 which are threadedly received on these rods. The adjusting bolt 69 is received in end 68b of rocker arm 68 and is held in adjustment by jam nut 69a.

Since the point of attachment to tank 46 is an intermediate point on arm 68, the end 68b experiences downward movement relative to the tank 46 when the tank shifts downwardly. Consequently, a charge of gluing fluid is forced through the passage 64b into the felt pad 60 each time the tank shifts downwardly.

The tank structure has no tendency to leak since the solvent admitted to the applicators 62 is in direct proportion to the requirements of these applicators in painting the cigarette packages.

The stamping mechanism

The structure of the stamping mechanism may best be seen in the views of Figures 13 and 14. The stamps are pressed against the tops of the cigarette packages 20a and 20b, Figure 14, by the hammer mechanism indicated generally at 72. This mechanism includes a pair of plungers 74 which are attached at their lower ends to a common head member 76.

The plungers 74 are received in suitable holes in the support arm 78 which projects from base or frame 52. At their upper ends, plungers 74 are connected by cross bar 80 against which the compression springs 82 bottom.

Up and down movements are imparted to plungers 74 by the rocker arm 84 which is pivotally supported at end 84a on the post 86, Figure

13, and at its intermediate portion 84b, the rocker arm 84 is pivotally attached to link 88 which is in turn pivotally attached to rocker arm 90 (Figure 19). The center portion of the latter is pivotally supported from base 52 by shaft 52a and at end 90a it receives the roller 92 which rides on cam 94.

When the link 88 is pulled downwardly under the action of rocker arm 90 riding on cam 94, the rocker arm 84 swings in the counter-clockwise direction and depresses the head 76 of plungers 74 against the top of the packages 20a and 20b. As will be described in further detail hereafter, a stamp is positioned over the portion of each package painted with solvent so that this action affixes a stamp to each package.

The cam rocker arm 90 is held against cam 94 by the tension spring 91, Figure 14, which is attached at its opposite ends to rockable arm 89 and the base 52. Arm 89 engages rocker arm 90 to hold the latter against cam 94.

The rocker arm 90 has an extended portion 90b which serves as the movable blade of a shears to cut the stamps in unison with the stamping action of the hammer mechanism 72. Portion 90b acts against the stripper plate 96 which is the fixed blade of the shears and which forms a table upon which the tapes forming the stamps rest as they are fed underneath the plungers 72.

The stamp feeding mechanism

Stamps are fed underneath the plungers 72 and knife 90b by the fingers 98, Figures 1 and 16. These fingers are mounted in spaced positions on the sleeve 100 which is carried on rockable lever arm 102, Figure 16, which is pivotally supported from frame 52. A crank arm 103 is behind arm 102, Figure 16, and is mounted for rocking movements therewith under the driving action of link 104. The latter is connected to oscillating lever 106 as is described in further detail hereafter. These elements are seen in enlarged top plan view in Figure 11.

The fingers 98 each ride on a tape made up of a succession of uncut stamps having central openings to receive these fingers. Each tape extends from a roll R, Figure 10, supported on the arm 108. As indicated at 109, Figure 10, each tape extends from the roll R to the guide roller 110 and then to the table 96 where it is engaged by the corresponding finger 98.

When the lever 106 is oscillated in timed sequence with the movements of the packages being stamped, the lever arm 102, Figure 16, is rocked and the fingers 98 execute corresponding reciprocating movements. These fingers successively engage the spaced openings in the tapes 109, thereby shifting the tapes forwardly by the distance corresponding to one stamp and positioning successive stamps under the knife 90a and the plungers 72.

The trigger mechanism

In order to prevent loss of stamps and gluing fluid and the jamming of the mechanism incident thereto, a trigger mechanism is provided to cause the operative elements to operate only when a carton is positioned for stamping. The construction of this trigger mechanism is best seen in the enlarged broken away top plan view of Figure 11. It is shown in elevation in Figure 16.

The trigger comprises a lever 114 swingably mounted on the frame 52 and having the plate 112 attached to the end 114a. The plate 112 extends through the guide 38 to present an edge

112a which is engaged by a carton C as it travels along the track T. At its opposite end, 114b, the crank 114 is attached to the trip latch 116 which is mounted in position to engage the tripping element of the clutch 118 to release shaft 122 and avoid driving the same as the gear 120 is rotated.

The trigger is normally held in the engaged position of Figure 11 by the spring 115 which is received on pin 115a of trigger 114 and on pin 115b which is held on frame 52.

The one revolution clutch 118 may be any one of several types well known in the art. It may, for example, include a helical spring with a protuberance defining a trip element to engage the latch 116 to unwind the spring as the gear 120 is rotated. In the unwound condition, the spring releases the shaft 122 and thus rotation of gear 120 imparts no motion thereto. However, when the spring is released by swinging latch 116 out of the path of movement of the protuberance, the spring snaps shut and establishes a driving connection between gear 120 and shaft 122. This driving connection is disengaged after the first revolution if the trigger 112 is released to swing to the position of Figure 11, where it again arrests movement of the protuberance of the clutch 118.

Thus when a carton C actuates the trigger 112, the shaft 122 is rotated at least one revolution and may continue rotation if the trigger 112 is held in the actuated condition.

The trigger 114 and the latch 116 are supported by the finger 124 which forms a rest against which latch 116 bears when holding clutch in the disengaged position.

The drive mechanism.

The drive mechanism actuates the tank F, and the stamping mechanism S in timed sequence following actuation of trigger 114. This is accomplished by means of the cams 58, 94, 128 and 130. Cams 58, 94, and 128 are alike and are attached to the shaft 122 to be rotated when the clutch 118 is released.

The shape of the cams 58, 94, and 128 is best seen in Figure 12, which shows cam 58. As indicated each of these cams is divided into six segments, five of which have protuberances, these protuberances being indicated at 58a, 58b, 58c, 58d, and 58e. The cam segment not having a protuberance which provides a dwell during which the cam produces no action. Cams 94 and 128 may be seen in the views of Figures 14 and 13, respectively.

It will be observed that the cam 94 is delayed by one segment relative to the cam 58 when the shaft 122 is rotated in the direction of arrow 129, Figures 12 and 14. In other words, the cam follower 54 rides on the protuberance 58a while follower 90a rides on a dwell. Then follower 54 rides on protuberances 54b, 54c, 54d and 54e while follower 90a rides on protuberances 94a, 94b, 94c and 94d. Finally, follower 90a rides on protuberance 94e while follower 54 rides free of any protuberances.

Since the tank F is actuated each time the follower 54 travels over a protuberance, and knife 90b and hammer 72 are simultaneously actuated each time follower 90a travels over a protuberance, the tank T and the knife 90b and hammer 72, each undergo a succession of five equally spaced operations for each revolution of shaft 122. However, the operations of the knife and hammers are delayed in time from the operations

of the tank by the time period between successive operations.

The shaft 122 is driven from the pulley 49 by the mechanism which may be traced from pulley 49 to bevel gear 131 to the mating bevel gear 132 and countershaft 134, Figure 14. The latter carries gear 139 which drives clutch 118 through gears 138 and 140. The sizes of these gears are proportioned relative to each other to cause the shaft 122 to rotate one revolution for each six revolutions of the shaft 50, thus causing one revolution of shaft 122 to correspond to six step-by-step forward movements of the carton C.

The cam 128 receives the lever 106 which in turn actuates the feeding fingers 98, Figure 11. For this purpose, the lever 106 has a sleeve 106a which rolls freely on the surface of cam 128 and actuates the feeding fingers each time a protuberance on the cam rides under the sleeve. It will be observed from Figure 13 that the cam 128 is positioned to lead the cam 94 by approximately one-twelfth revolution. Thus the fingers 98 are actuated and inject the stamps under knife 90a and the hammers 72 just prior to the simultaneous strokes of these latter elements.

The extending portion 106b of the lever 106 receives the spring 107, Figure 1, which urges that end of the lever against cam 128.

It will be observed that the sequence of operations due to each of cams 128, 94 and 58 is delayed relative to the time of actuation trigger 114 by the time required for the packages to move from the trigger to the points at which operations take place. Since the painting operation controlled by cam 58 is accomplished at the same point as trigger 114, as will be evident from Figure 16, the up and down movements of the tank F commence immediately after the trigger is actuated. However, since the plungers 74 are spaced from trigger 114 by the center-to-center distance of the adjacent packages (and hence the distance of one step in the movement of the packages) the cam 122 does not actuate the plungers 74 and knife 90b until the time required for this movement of the packages.

The function of cam 130, Figures 11 and 13, is to equalize the countertorque on shaft 122 and to hold that shaft stationary when the clutch 118 is in the disengaged condition. To this end, cam 130 has an indentation 130a, Figure 13, in which the cam follower 132 rides as shown in Figure 13. The cam follower 132 is urged against cam 130 by the spring 134.

The carton gluing and folding mechanism.

The mechanism for gluing and folding the carton C is shown in Figures 10 and 17 to 21. As shown in these views a supplementary glue tank 136 is mounted adjacent track T and under the path of travel of tongue 22 of carton C. This tank has an elongated end portion 136a open at the top and having opposite notches 136b in the upper ends of the side walls to receive the support for the glue applying arm 137. This arm supports rollers 140 and 140a which carry the glue in tank 136 from the bottom thereof to the path of travel of tongue 22 of carton C. The arm 137 is supported for rocking movements in the tank 136 by the pin 137a which is journaled in notches 136b.

The flap 24 and tongue 22 of the carton are freed for opening movements by the triangular knife 26, Figures 1 and 20. This knife is mounted at the proper height above track T to be received under flap 24, thus cutting that flap free when

the carton is shifted to the left, Figure 1, and then to the right to cause the edges 26a and 26b, respectively, to cut the carton.

As shown in Figure 18, the tongue 22 and the flap 24 of carton C are opened up as that carton travels underneath the cam 27. Further forward movement causes tongue 22 to ride under the hood 29, Figures 10 and 19, which holds that tongue against roller 140a as it travels thereover, thus applying glue to the bottom face of tongue 22 as the sequence of stamping operations is conducted on the packages therein by tank F and other components of the mechanism.

The carton C then travels to cams 34 and 36, Figures 1 and 21, which refold tongue 22 and flap 24, respectively, to restore the carton to a closed condition.

The mechanism of the present invention may be adjusted to handle packages of greater size by lowering the track T and raising the knife 26 and the cam elements 26, 34 and 36 relative thereto. Track T may be conveniently lowered by shifting bolts 142 to the upper holes 144, Figure 10, in the frame structure provided for the track. This does not alter the throw of the crank 44 sufficiently to vary the operation of the track mechanism.

The gluing fluid in the tank F is a solvent suitable for use with cement or glue coated on the tape 109. This solvent cooperates with the plastic sheet covering on the packages securely to affix the stamps to the packages.

The fluid in tank 136 may be any mucilage or like material capable of holding the cardboard tongue 22 to the top wall or flap 24 of the carton C to close the carton.

While I have shown and described a specific embodiment of the present invention it will, of course, be understood that I do not wish to be limited thereto since many modifications and alternative constructions may be made without departing from the spirit and scope thereof.

What I claim as new and desire to secure by Letters Patent of the United States is:

1. In an apparatus for applying stamps to an array of adjacent packages held by a jacket open at one edge to expose said packages, conveyor means operative to propel said jacket in step-by-step forward movements corresponding to the center-to-center spacing of said packages in the direction of movement, means operative to paint said packages with gluing fluid as they successively stop at a predetermined point of movement, and mechanism operative to press stamps against said packages as they successively stop at a further point.

2. In an apparatus for applying stamps to a tape to an array of packages held by a jacket open at one edge to expose said packages, the improvement which comprises conveyor means to propel said packages in step-by-step forward movements corresponding to the center-to-center spacing of said packages in the direction of movement, a stripper plate mounted above a predetermined point in the path of travel of said packages, mechanism operative in timed sequence with the movements of said conveyor to feed said stamps to said stripper plate, and means operative in timed sequence with said conveyor but delayed with respect to said mechanism simultaneously to cut said tape to sever individual stamps and to press said stamps against said packages.

3. In an apparatus for applying stamps to an array of packages held by a jacket open at one edge to expose said packages, conveyor means to

propel said packages in step-by-step forward movements corresponding to the center-to-center spacing of said packages in the direction of movement, means operative to paint said packages with gluing fluid as they successively stop at a predetermined point of movement, means to guide a tape of stamps to a point adjacent said packages as they stop at a predetermined further point in their forward movement, means operative in sequence with said conveyor means to feed said stamps to said point, cutting means operative in sequence with said conveyor means to cut successive stamps from said tape, and mechanism operative to press said stamps against said packages as they stop at said last point.

4. In an apparatus of the type where an array of packages is bodily propelled in step-by-step movements along a predetermined path, a trigger positioned for actuation by said array of packages, means responsive to actuation of said trigger to execute operations on said packages at a predetermined point in the movement thereof, said means including elements operative to initiate a sequence of operations spaced in time by the said movements and equal in number to the packages in said array, the first of said movements being delayed in time by the time required for said packages to travel from the position of said trigger to said predetermined point.

5. In an apparatus of the type wherein a succession of operations are performed on each of an array of packages as the entire array is bodily propelled along a predetermined path in step-by-step movements, a trigger positioned to be actuated by said array as it travels past a predetermined point in said path, and a plurality of mechanisms at spaced points on said path operative in response to actuation of said trigger to execute said operations, each of said mechanisms being operative to execute a succession of said operations spaced in time by the said movements and equal in number to the number of packages of said array, the first operation of each of said mechanisms being delayed in time from the time of actuation of said trigger by the time necessary for said packages to travel from said first point to the point of action of the corresponding means.

6. In an apparatus of the type wherein an operation is executed on each of an array of packages as the entire array is bodily propelled along a predetermined path in step-by-step movements, a trigger positioned for actuation by said array as it travels past a predetermined point in said path, a cam having a plurality of equally spaced operating segments equal in number to the number of packages in said array and spaced by a blanking segment, a cam follower operatively associated with said cam to be actuated upon travel over said operating segments, means to execute said operation on said packages as said follower is actuated, and means to rotate said cam over a full revolution upon actuation of said trigger, the blanking segment of said cam being positioned to delay said operations by the time required for said packages to travel from said trigger to said predetermined point and the angular distance between said operating segments thereof being such as to space said operations by the said first movements.

7. In an apparatus for applying stamps to an array of packages held by a jacket open at one edge to expose said packages, conveyor means to propel said jacket in step-by-step movements corresponding to the spacing of said packages, a trigger positioned to be actuated when said

jacket reaches a predetermined point of movement, mechanism operative to paint said packages with gluing fluid at a predetermined point of movement, mechanism operative to press stamps against said packages at a predetermined further point of movement, and elements operative in response to actuation of said trigger to actuate each of said mechanisms in a succession of operations equal in number to the number of packages in said array and spaced in time in accord with the said step-by-step movements, the succession of operations initiated by said last means being delayed in time from the actuation of said trigger in accord with the distance between said trigger and the corresponding mechanisms.

8. In an apparatus for applying stamps to an array of packages held by an enclosing jacket having a tongue at one edge which is opened to expose said packages, conveyor means to propel said jacket along a predetermined path in step-by-step movements corresponding to the center-to-center spacing of said packages, means defining a cam surface to receive said flap and open said flap at a predetermined point on said path and to close said flap at a later predetermined point on said path, means to apply glue to said flap at a point intermediate said predetermined points, mechanism operative to paint said packages with gluing fluid as they successively stop at a predetermined point intermediate said first predetermined points, and elements operative to press stamps against said packages at a predetermined point further along said path of travel than said last predetermined point but intermediate said first two predetermined points.

9. In a machine for applying stamps in a tape to a succession of packages travelling past a predetermined point, the improvement which comprises a stripper plate adjacent said predetermined point, means to feed said tape across said plate in a succession of stepped movements, a knife operative in timed sequence with said last means to sever stamps from said tape, and means operative in unison with said knife to engage said severed stamps and press them against said packages.

10. In the method of applying stamps to an array of packages held in a jacket, the steps of propelling said jacket in step-by-step movements corresponding to the center-to-center spacing of said packages and along a predetermined path, painting said packages with gluing fluid as they successively pass a predetermined point of travel, and pressing said stamps against said packages as they pass a predetermined later point of travel.
